UNITED STATES PATENT OFFICE.

JAMES A. BROGAN, OF LAWRENCE, MASSACHUSETTS, ASSIGNOR TO UNITED SHOE MACHINERY CORPORATION, OF PATERSON, NEW JERSEY, A CORPORATION OF NEW JERSEY.

FASTENING-INSERTING MACHINE.

Application filed June 4, 1920. Serial No. 386,545.

To all whom it may concern:

Be it known that I, JAMES A. BROGAN, a citizen of the United States, residing at Lawrence, in the county of Essex and State 5 of Massachusetts, have invented certain Improvements in Fastening-Inserting Machines, of which the following description, in connection with the accompanying drawings, is a specification, like reference characters on the drawings indicating like parts in the several figures.

This invention relates to fastening inserting machines, and an object of the invention is to improve machines of the kind designed 15 to sever nails from a nail string and drive them into the work.

A further object of the invention is to provide a machine for inserting string nails which will be adapted to operate on a nail 20 string composed of relatively soft stock, for example, iron or brass wire, and to this end an important feature of the invention resides in the provision in a string nailing machine, of mechanism for severing the nails 25 from the nail string and presenting them to the driver of the machine, constructed and arranged to form oppositely beveled surfaces on the points on the nails, thus enabling them to be driven straight into the 30 work and also facilitating the proper clinching of the nails.

The illustrated machine is of the type comprising a fastening receiving member having a passage to receive the endmost 35 nail of a nail string and a nail string guide having a guideway for the nail string and movable relatively to the fastening receiving member to aline the guideway with the passage of the fastening receiving member 40 to enable the nails to be fed into the passage, and a further feature of the invention resides in the provision in such a machine of means independent of the nail string guide and the means by which the nails are fed for 45 severing the nails from the nail string after they have been introduced into the fastening receiving member.

Other objects and features of the invention will appear as the description proceeds 50 and will be pointed out in the appended claims.

In the drawings,

Fig. 1 is a view in front elevation of the

superstructure of a string nailing machine according to the invention;

Fig. 2 shows a nail string of a form which 55 it is contemplated to utilize in the illustrated machine;

Fig. 3 is a view in perspective of the nail 60 string guide and the operating connections therefor;

Fig. 4 is a view in perspective of the lower portion of the nail string guide, showing 65 the die plate against which the nails are severed from the nail string;

Fig. 5 is a view in cross-section of the nail string guide and the cutter by which 70 the nail strings are severed against the guide;

Fig. 6 is a view on an enlarged scale of 75 the feeding and severing means for the nail string and their operating connections;

Fig. 7 is an enlarged view of the lower portion of the swinging head of the machine 80 and the parts associated therewith; and

Figs. 8 and 9 are views similar to Fig. 75 but showing the parts as they appear at other points in the cycle of operations of the machine.

The illustrated machine comprises a column 2, upon which rests a superstructure 4, on the front of which is supported a head 6 swingingly mounted on a shaft 8 journaled in the superstructure 4. The swinging head 6 is maintained against the front of the 85 superstructure 4 by castings 10. Slidably mounted in the swinging head 6 are a driver bar 12 carrying a driver 14 and an awl bar 16 carrying an awl 18. The driver bar 12 is raised by a cam on the shaft 8 operating 90 against a block 20 on the bar, and is depressed to drive the nails by a spring 21 coiled about a part on the superstructure 4. The awl bar 16 is provided with teeth 23 with which mesh the teeth of a segment gear 95 22 fixed to a shaft 24 journaled in the superstructure 4. An arm 26 on the shaft 24 carries a roll 28 riding in a cam groove 30 formed in a cam 32 on the shaft 8. The head 6 is swung to and fro on the shaft 8 100 by means including a block 33 adjustable in a groove in the head 6, as clearly appears from Fig. 1. On the lower end of the head 6 is a fastening receiving member in the form of a throat 34 having substantially vertical passages 36 and 38 through which the

55

65

75

100

105

driver 14 and the awl 18 respectively reciprocate. The nails to be driven are successively introduced into the passage 36 when the driver is elevated out of the passage. Preferably, and as shown, the nails are controlled during their movement through the throat passage 36 by a spring pressed finger 39 pivoted in the throat 34.

The nail string is supplied to the machine 10 on a reel 40 supported on the superstructure 4 by a bracket 42. The nail string is wound on the reel 40 and the reel is applied to the machine in such a manner that in the operation of the machine the nail string will 15 be unwound from the top of the reel with the nails in the string arranged points down and with their heads disposed outwardly from the string, or to the left, as seen in Fig. 1. The nail string, as it is drawn from 20 the reel passes through a guiding tube 44 mounted on the bracket 42, and the end of the string is introduced into a guideway 46 formed in a nail string guide 48. As shown, the guide 48 is formed with two guideways 25 46 to enable two nail strings of different characters to be supplied to the machine, and the nail strings are retained in the guideways by leaf springs 50 secured to the guide 48 by set screws or the like 52. When 30 two nail strings are supplied to the machine the reel 40 and guide 44 are duplicated. The nail string guide 48 is carried by a shaft 54 fulcrumed in the head 6 of the machine. In order to oscillate the guide 48, 35 the shaft 54 is provided with an arm 56 carrying a cam roll 58 disposed to ride on the periphery of the cam 32. The cam roll of the arm 56 is maintained against the periphery of the cam 32 by a spring 60. 40 The shaft 54 is mounted for endwise movement in the head 4 to the end that the nails in the guideways 46 of the guide 48 may be selectively presented to the passage 36 of the throat 34. The endwise movement 45 of the shaft 54 is effected in the illustrated machine by mechanism including a hand lever 62 appearing at the right-hand side of the machine, as seen in Fig. 1. The mechanism thus far described constitutes 50 by itself no part of the present invention and is clearly disclosed in United States Letters Patent No. 1,401,247, granted Dec. 27, 1921, on an application of George Goddu and Fred L. Mackenzie. A more complete 55 description of such mechanism is accordingly deemed unnecessary.

The nail strings on their way from the guides 44 to the guideways 46 in the guide 48 pass through a supplementary guide 64 60 carried by a strip 66 pivoted at 68 on the machine frame and having an upwardly extending portion 70 normally engaging a lug 71 on the casting 10.

The nail string is intermittently fed to

introduce the endmost nail of the nail string 65 successively into the passage 36 of the throat 34 by means including a blade 72 mounted in a holder 74, in which it may be adjusted by a screw or the like 76. A set screw 78 on the side of the holder 74 serves to secure 70 the blade 72 in adjusted position in the holder. In the present instance of the invention, the holder 74 is carried by an arm 80 mounted on a shaft 82, upon which is coiled a spring 84 tending normally to press 75 the blade 72 against the opposite surface of the nail string guide 48. A cam roll 86 on the lower end of the arm 80 is disposed to ride on a cam surface 88 on the rear edge of the laterally extending portion 90 of the nail string guide 48. The cam surface 88 accordingly controls the blade 72 in its position with respect to the nail string guide 48. The shaft 82 is sleeved into the end of an arm 92 pivoted loosely on a shaft 94 85 journaled in the head 6 of the machine. As shown, the arm 92 is extended rearwardly from the shaft 94 and is formed with a bowed portion 96, which terminates in an upwardly extending bar 98 channeled to 90 receive a sliding block 100, to which is pivoted a lever 102 having a cam roll 104 at its upper end riding in the cam groove 90 of the cam 32. The cam 32 through the operating connections above described reciprocates the blade 72 in a substantially vertical direction along the side of the nail string 95 guide 48.

The illustrated machine is particularly designed to operate on nail strings of relatively soft material, such a nail string being shown in Fig. 2 and consisting of a wire bent or folded upon itself at intervals as indicated at A to constitute the heads of the nails in the string and having portions cut 100 away at B to assist in forming points on the shanks of the nails. The wire may be made of iron or brass, for instance, but is preferably soft enough to enable it to be cut or bent readily. In accordance with the invention, means is provided for severing the endmost nail from the nail string after 105 it has been fed into the passage 36 of the throat 34 of a character to cause the nails to penetrate the work easily, so that they will not buckle when they are driven, and to be otherwise properly inserted into the work. As shown, such means comprises a die plate 106 recessed into the lower end of the nail string guide 48 and maintained in 110 place on the guide by a headed pin or the like 108. The cutting edge 110 of the die plate 106 is formed at the intersection of its lower surface 112 and the surface contiguous to the path of movement of the nail 115 string. The die plate 106 is so disposed with relation to the upper surface of the throat 34 that when the endmost nail of the nail 120

string has been fed into the throat the portion of the nail string at the junction of the head of the nail in the throat and the point of the second nail is presented against the 5 edge 110 of the die plate. The die plate 106 is ground off above the edge 110 so as to cause its surface 114 to be disposed at an acute angle to its lower surface 112 and to be spaced inwardly from the inner surfaces 10 116 of the guideways 46 of the nail string guide 48. Consequently, the point of the second nail in the string is presented to the cutting edge 110 of the die plate 106 at an angle to the contiguous surface 114 of the 15 plate. As shown, the inclination of the surface 114 to the shank of the nail is increased adjacent to the edge 110, as indicated at 118, but it is apparent that like results may be obtained by continuing the surface 114 at 20 the same angle to the shank of the nail as at the portion 118.

In the present instance of the invention, the nail string severing means further comprises a cutter 120 having its edge disposed 25 to about substantially against the edge 110 of the die plate 106 and being beveled backwardly and upwardly from its edge, thus presenting a beveled surface opposite the portion 118 of the surface 114 of the die 30 plate 110. With this construction, when the cutter 120 is operated to sever the endmost nail from the nail string against the edge 110 of the die plate 106, oppositely beveled surfaces are formed on the point of the second nail by the beveled end of the cutter 120 and the inclined surface 114 of the die plate 106, thus enabling the nail to be easily inserted into the work and by reason of the 35 fact that the point of the nail is about 40 equally beveled on each side, practically insuring that the nail will be driven straight into the work. In making the nail string, the wire is preferably cut more than half the way through at the points B, so that the 45 points of the nails when they are severed from the nail string by the nailing machine are also reduced on their sides intermediate between the beveled surfaces formed by the cutter 120 and the die plate 106. In this 50 way, a point is formed on the nails which not only enables them to be driven straight but which may also be perfectly clinched. The cutter 120 is dovetailed into the split lower end of a holder 122, as shown in Fig. 8, and 55 may be maintained in any desired position of adjustment in the holder 122 by a headed screw 124. Preferably, and as shown, a post 125 is formed on the holder 122 in position to abut against the opposed surface of the 60 nail string guide 48 in order to facilitate the setting of the blade 120 in the holder. The holder 122 is pivoted on the nail string guide 48 by means of a pin 126 extending laterally from the nail string guide and passing 65 through the forked upper end of the holder.

A bar 128 secured rigidly to the swinging head 6 has its lower end extended forwardly (see Fig. 6) and received within the forked upper end of the holder 122 in order to constrain the holder and, consequently, the cutter 120 against movement with the nail string guide when it is shifted to move one of the guideways 46 of the nail string guide out of and the other into operative relation to the nail receiving passage 36 of the throat 34. 70 In order to provide for the relative movements of the head 6 and the nail string guide 48, the bar 128 is formed at its point of connection with the pin 126 with an elongated slot 130. The cutter holder 122 is moved 80 away from and toward the nail string guide 48 to permit the nail string to be fed and to cause the cutter 120 to sever the nail string against the edge of the die plate 106 carried by the nail string guide by means including 85 a link 132 composed of rods united by an expansible connection 134. As shown, the link 132 is connected to the cutter holder 122 by a screw 136 and is joined at its other end by a pin 140 to an arm 138 mounted on the shaft 94. Formed integrally with the arm 138 is an arm 142 carrying a roll 144 riding on the periphery of a cam 146 fixed on the shaft 8. The cutter 120 moves in a substantially horizontal path which is somewhat curved because of the pivotal mounting of the cutter holder 122, and the upper surface of the throat 34 is curved at 147 to permit such movement of the cutter. 90 95

The work is presented to the machine on a horn 148 which upholds it against a guard plate 150 which, in turn, is provided with a slot opening toward the right, as seen in Fig. 1, to receive the throat 34. 100

The manner of operation of the illustrated machine will now be described. Assuming that a nail has just been driven by the machine, the parts will be in the positions shown in Fig. 7, wherein the swinging head 6 is substantially at the limit of 110 its movement to the right, and the driver 14 is in its downward position. At the same time, the awl occupies an intermediate position in the awl passage 38 of the throat 34. In the continued operation of the machine, 115 the awl moves downwardly into the work, and the nail string guide 48 is shifted somewhat to the left away from the driver. Meanwhile the nail string feeder 72 is raised to engage over the head of the endmost nail 120 in the nail string. The driver 14 moves up at the same time as the feeder 72, completing its upward movement a short time after the feeder attains its uppermost position. After the driver 14 has been fully raised, 125 the head 6 is swung to the left about the shaft 8, the nail string guide 48 and the cutter 120 moving with it. When the swinging head 6 has nearly completed its movement toward the left, the awl bar 16 is 130

raised to withdraw the awl 18 from the work which has then been fed, and the nail string guide 48 is shifted toward the right to align one of its guideways 46 with the passage 5 26 of the throat, the cutter 120 being simultaneously moved toward the left to open up a space between itself and the die plate 106 to permit the nail string to be fed. After the last-mentioned movements of the 10 nail string guide 48 and the cutter 120 are completed, the feeder 72 moves downwardly to feed the nail engaged by it into the throat passage 36. The awl bar 16 completes its upward movement when the feeder 15 72 is about half-way down and starts down again during the final part of the movement of the feeder. When the feeder 72 has completed its downward movement and has fully inserted the endmost nail of the nail 20 string into the throat it is raised to permit the cutter 120 to be operated. The cutter is then moved forwardly or toward the right, as seen in Figs. 7, 8, and 9 along the head of the nail in the throat to sever it from the 25 remainder of the nail string. At the same time, the head 6 is swung back toward the right to bring the nail receiving passage into the line of drive of the nails and into line with the opening made in the work by 30 the awl 18. Upon the completion of the movement of the swinging head 6 toward the right, the nail string guide is moved slightly toward the left to make clearance 35 for the driver 14 which is then forced downwardly by the spring 21 to drive the nail into the work.

Having thus described my invention, what I claim as new and desire to secure by Letters Patent of the United States is:—

- 40 1. In a machine for inserting string nails, a throat having a substantially vertical nail receiving passage, means for guiding the endmost nail of a nail string into the passage of the throat, means for reciprocating the throat, means for feeding the work upon movement of the throat, means movable substantially vertically for feeding the endmost nail of the nail string into the throat, and means independent of the nail string 45 guide and the throat and movable substantially horizontally to sever the endmost nail from the nail string.
2. In a machine for inserting string nails, a throat having a nail receiving passage, means for imparting a to and fro movement to the throat, means for feeding the work upon movement of the throat, a guide for conducting the endmost nail of a nail string into the throat, means for feeding the nail 55 string, and means operable independently of the throat and the feeding means to sever the endmost nail from the nail string after it has been fed into the nail receiving passage of the throat.
- 60 3. In a machine for inserting string nails,

a fastening receiving member having a passage to receive the endmost nail of a nail string, a nail string guide movable relatively to the fastening receiving member, means for feeding the nail string, a cutter 70 co-operating with the guide to sever the endmost nail from the nail string after it has been fed into the passage of the fastening receiving member, and means for operating the cutter constructed and arranged to 75 move the cutter away from the guide previous to the feeding of the nail string and to maintain the cutter in spaced relation to the nail string guide while the nail string is being fed.

4. In a machine for inserting string nails, a throat having a nail receiving passage, a nail string guide formed to present a guideway movable into alignment with the passage of the throat and operable to conduct the 85 endmost nail of a nail string into said passage, means for feeding the nail string, and a cutter movable independently of the guide and the feeding means for severing the endmost nail from the nail string after 90 it has been fed into the passage of the throat, the means for feeding the nail string being arranged for movement in the direction of feed independently of the cutter.

5. In a machine for inserting string nails, 95 an awl operative to penetrate and feed the work, a nail string guide, a die plate supported by the guide and having surfaces disposed at an acute angle to each other and meeting at an edge, means for presenting a nail string to the die plate constructed to position the portion of the nail string at the junction of the point of a nail and the head of another against the edge of the die plate with the shank of the first-mentioned 105 nail disposed at an angle to the contiguous surface of the die plate, and a cutter co-operating with the edge of the die plate to sever the nails from each other.

6. In a machine for inserting string nails, 110 an awl operative to penetrate and feed the work, a die plate having surfaces disposed at an acute angle to each other and meeting at an edge, means for presenting a nail string to the die plate constructed to position the portion of the nail string at the junction of the point of a nail and the head of another against the edge of the die plate and to arrange the shank of the first-mentioned nail at an angle to the contiguous 120 surface of the die plate, and a cutter movable in a path substantially parallel to the other surface of the die plate toward and from the edge of the die plate to sever the nails from each other, the cutter being 125 formed with a bevel to cause a bevel on one side of the point of the nail and the contiguous surface of the die plate forming a bevel on the other side of the point of the nail.

7. In a machine for inserting string nails, an awl operative to penetrate and feed the work, a die plate having surfaces disposed at an acute angle to each other and meeting at an edge, means for supporting the die plate, means for presenting a nail string to the die plate constructed to position the portion of the nail string at the junction of the point of a nail and the head of another against the edge of the die plate and to arrange the shank of the first-mentioned nail at an angle to the contiguous surface of the die plate, and a cutter for severing the nails from each other against the edge of the die plate having its edge disposed to abut substantially against the edge of the die plate and being formed with a beveled surface opposite from the contiguous surface of the die plate, so that when a nail is severed from the nail string, the point of the next nail in the string is beveled on opposite sides.
8. In a machine for inserting string nails, a driver, a nail string guide and a cutter independent of the driver and co-operating with the guide to sever the nails from the nail string, said nail string guide and cutter being constructed and arranged to form beveled surfaces on opposite sides of the points of the nails.
9. In a machine for inserting string nails, a driver, and means for severing nails from a nail string and presenting them to position to be inserted into the work by the driver constructed and arranged to bevel the points of the nails to facilitate their insertion by said driver.
10. In a machine for inserting string nails, a throat having a substantially vertical nail receiving passage and a substantially horizontal upper surface, a nail string guide for conducting the endmost nail of a nail string into the nail receiving passage, means for feeding the endmost nail of the nail string into the throat passage by engagement with the head of the nail, means for withdrawing the feeding means from engagement with the head of the nail after it has been fed into the throat passage, and a cutter movable along the upper surface of the throat subsequent to the withdrawal of the feeding means to sever the endmost nail from the nail string.
11. In a machine for inserting string nails, a throat having a nail receiving passage, a nail string guide movable relatively to the throat and operable to conduct the endmost nail of a nail string into the throat, means for feeding the endmost nail of the nail string into the throat by engagement with the head of the nail, and a cutter movable along the head of the endmost nail of the string into engagement with the point of the next adjacent nail to sever the endmost nail from the nail string.
12. In a machine for inserting string nails, a fastening receiving member having a passage to receive the endmost nail of a nail string, means for presenting a nail string to the fastening receiving member comprising a guide for the nail string, means for moving the guide relatively to the fastening receiving member, and a cutter carried by the guide and movable relatively to the guide to sever the endmost nail from the nail string after it has been inserted into the passage of said member.
13. In a machine for inserting string nails, a fastening receiving member having a passage to receive the endmost nail of a nail string, means for presenting a nail string to said passage comprising a guide for the nail string, a die plate carried by the guide, and means carried by the guide and movable to sever the nail string against the die plate.
14. In a machine for inserting string nails, a fastening receiving member having a passage to receive the endmost nail of a nail string, means for presenting a nail string to the passage of the fastening receiving member comprising a guide for the nail string, a cutter, and a cutter holder fulcrumed on the nail string guide and operable to cause the cutter to sever the nail string against the guide.
15. In a machine for inserting string nails, a fastening receiving member having a passage to receive the endmost nail of a nail string, means for presenting a nail string to the passage of the fastening receiving member comprising a guide for the nail string, a cutter, a cutter holder supported on the guide for movement toward and from the lower edge of the guide, and separate means for operating the guide and the cutter holder.
16. In a machine for inserting string nails, a fastening receiving member, mechanism for presenting a plurality of kinds of fastenings to the member, said mechanism including guiding means having a plurality of guideways for the fastenings and said guiding means being shiftable relatively to the fastening receiving member to enable any one of the guideways to guide a fastening into the receiving member, a cutter carried by the guide for severing the nail string, and means for retaining the cutter against movement with the guide when the guide is shifted.
17. In a machine for inserting string nails, a fastening receiving member, mechanism for presenting a plurality of kinds of fastenings to the member, said mechanism including guiding means having a plurality of guideways for the fastenings and said guiding means being shiftable relatively to the fastening receiving member to enable any one of the guideways to guide a fasten-

ing into the receiving member, a cutter holder fulcrumed on the nail string guide and being forked at its upper end, and a member fixed on the head of the machine and received within the fork of the cutter holder to prevent movement of the cutter holder with the nail string guide when the nail string guide is shifted.

18. In a machine for inserting string nails, a fastening receiving member having a passage to receive the endmost nail of a nail string, a nail string guide movable relatively to the fastening receiving member, a cutter carried by the nail string guide, and means for moving the cutter toward and from the nail string guide to permit the nail string to be fed between the cutter and the guide and to sever the nail string against the guide.

19. In a machine for inserting string nails, a fastening receiving member having a passage to receive the endmost nail of a nail string, an oscillating guide for conducting the endmost nail of a nail string into said passage, means for feeding the nail string by engagement with the head of a nail in the string, a cutter for severing the endmost nail from the string after it has been fed into the passage of the throat, and a holder for the cutter movably mounted on the nail string guide.

20. In a machine for inserting string nails, a fastening receiving member having a passage to receive the endmost nail of a nail string, a guide for conducting the endmost nail of the nail string into the passage of said member, a cutter holder movable toward and from the nail string guide, a cutter movably mounted in the cutter holder, and a post on the cutter holder disposed for engagement with the nail string guide to

facilitate the setting of the cutter in the holder with relation to the guide.

21. A machine for inserting string nails having, in combination, a drive shaft, a driver operated from said shaft, and means for severing nails from a nail string constructed and arranged to bevel both sides of the points of the nails as they are severed from the string to facilitate their insertion by said driver.

22. A machine for inserting string nails having, in combination, an awl arranged to penetrate and feed the work, means for severing nails from a nail string constructed and arranged to bevel both sides of the points of the nails as they are severed from the string, and a driver operative to insert the severed nails in the holes formed in the work by the penetration of the awl.

23. A string nail inserting machine having, in combination, a driver and means alternatively to sever nails from one of a plurality of nail strings constructed and arranged to bevel the points of the nails to facilitate their insertion by said driver.

24. A string nail inserting machine having in combination, a drive shaft, a driver operated therefrom, a die having a surface inclined with respect to a nail of a nail string presented thereto and having a cutting edge, a cutter having a surface terminating in a cutting edge and inclined with respect to said nail, and means for operating the cutter and die to sever nails from the nail string and to bevel the points of the nails to facilitate their insertion by said driver.

In testimony whereof I have signed my name to this specification.

JAMES A. BROGAN.
